SUPERHEATING BOILER

Knut Berger, Seattle, Wash.

Application July 12, 1933, Serial No. 680,073

8 Claims. (Cl. 122—467)

This invention relates to improvements in steam generating boilers and more particularly to vertical, fire tube boilers of that type having an extended fire box; it being the principal object of this invention to construct boilers of the above stated character including steam super-heater units. Also, it is contemplated that the present invention shall apply, first, to the manufacture of boilers with the present super-heater units embodied therein as original equipment and, second, to the conversion of boilers of the above stated type, which originally were not equipped with steam super heating means, to boilers coming within the scope of the present invention by application of the present super-heater units thereto.

It is also an object of this invention to provide a super-heater unit for boilers of the above character which materially increases the heating surface of the boiler; effects better distribution of heat; provides an additional and an increased water circulation and a better circulation especially in the extended part.

Another object of the invention resides in the provision of a super-heater that gives easy accessibility to its flues or tubes for cleaning, repair or removal. Also in the provision of a super-heater unit that may be easily and readily applied to boilers already in use and without disturbing the boiler flues or flue sheets.

Another object is to provide a vertical fire tube boiler equipped with a super-heater and having means for controlling heating of the super-heater independently of the main boiler.

A still further object of the invention resides in the provision of a super-heater unit whereby a better distribution of heat is made possible by reason of direct intake of gases of combustion from the fire box into the super-heater.

Still further objects reside in the arrangement of the smoke box whereby the top flue sheet of the boiler is protected against moisture entering through the stack and whereby additional space is provided for accommodation of a water heater system.

Other objects of the invention reside in the details of construction of the various parts, in their combination and mode of operation as will hereinafter be described.

In accomplishing these and other objects of the invention I have provided the improved details of construction the preferred forms of which are illustrated in the accompanying drawings where-in—

55 Fig. 1 is a vertical, sectional view of a boiler em-

bodying a super-heater in accordance with details of the present invention.

Fig. 2 is a plan, or top view of the boiler.

Fig. 3 is a horizontal section through the upper portion of the boiler.

Fig. 4 is a detail of part of the super-heater damper and its control means.

Referring more in detail to the drawings—

1 designates, in its entirety, a vertical, water tube boiler embodying the present invention. In 10 the arrangement shown, the boiler comprises a cylindrical shell 2 enclosing a plurality of fire tubes 3 which are mounted at their upper and lower ends, respectively, in flue sheets 4 and 5 which close the corresponding ends of the shell. 15 The lower flue sheet 5 constitutes the top wall of the furnace fire box 6 which, in the type of boiler to which the present invention applies, is extended to some extent rearwardly of the shell. The fire box is encased within a water jacketing 20 housing 7 which is a continuation of or which joins with the lower end of the shell 2 and together with the fire box wall, provides water legs 8 entirely about the fire box. These water legs have free and open communication with the lower 25 end of shell 2 to permit easy circulation of water. An opening 10 is provided at the front of the fire box and there are draft openings 11 and 12 at front and rear, respectively, and adjacent the floor, equipped with suitable dampers as designated at 13, to control entrance of air for combustion.

In the present showing, an oil burner nozzle 14 enters the fire box through the front wall and there is a deflecting baffle 15 across the bottom 35 wall of the box just forwardly of the draft opening 13 to cause upward deflection of the flame from the burner and also to avoid any interference with air entering through opening 13. It is to be understood however, that various methods other than shown might be employed for heating the boiler and various other controls and dampers might be employed without departing from the spirit of the present invention; this merely being illustrative of a satisfactory construction.

Explanatory to the invention, it will here be mentioned that in the common types of vertical fire tube boilers now quite extensively used, super-heaters are not employed. In their usual arrangement, such boilers correspond generally to the boiler shown in Fig. 1, insofar as the shell, tubes and extended fire box are concerned but are without any provision for attachment or use of a super-heater. Also the stack is generally co-

axial of the shell. In such boilers, circulation of water in the fire box extension is not entirely satisfactory and heat of combustion is not distributed in the most effective manner. Furthermore, where the relatively large stack opening at the top is directly over the top flue sheet, moisture is permitted to enter and collect on the sheet with consequent damage thereto due to rust.

In the present application, it has been the intent to not only provide additional means in such boilers for the super-heating of steam, but also to cure to a material extent all the undesirable features which are above mentioned.

The super-heater embodied by this invention comprises a cylindrical shell 18 disposed vertically just rearwardly of the shell 2 and supported upon the top wall of the fire box extension. An opening 19 through this top wall provides for direct passage of heat, through the super-heater. A horizontally corrugated lining 20 is contained within the shell 18 and this is of such diameter that it provides an annular, intermediate space 29a for water circulation. This space has pipe connections 21-21 at opposite sides and near the lower end of the shell, with the water leg across the top of the fire box extension, and it has another pipe connection 22 near its upper end with the boiler shell 2, thus to provide the additional water circulation for the boiler. The pipe 22 is located just below the intended water level, as indicated at 24, and at a point above this level a connecting pipe 25 provides for by-passing of steam from the upper end of shell 18 into the shell 2 of the boiler proper.

The super-heater thus provides additional heating space over the area of its interior passage and the upper end of the passage opens directly into a smoke box 28 fitted upon and accommodating both shells 2 and 18. At a point directly over the super-heater, this box 28 is provided with an opening 29 for a stack connection and forwardly of the opening is a hingedly attached cover section 30 closing the top of the box. Removal of the cover provides an opening for installation of a water heater or the like, as designated in dotted lines at 32 in Fig. 1.

Contained within the super-heater shell are the steam super-heating coils 35. These consist of a plurality of closely arranged U-shaped pipes mounted at their upper ends in a conically dished plate 36; the plate being divided diametrically by a vertical partition wall 37 and the pipes are so mounted therein that each pipe opens at its opposite ends, respectively, through the plate 36 at opposite sides of the partition. The plate 36 is covered by a manifold 38 that is divided to provide two compartments 39 and 40 which co-operate with the divided conical plate 36 in such manner that they respectively communicate with opposite ends of the coils 35. The compartment 39, as seen best in Fig. 1, has a pipe connection 41 with the upper end of the main boiler through the top flue sheet 4 and the compartment 40 has connection with a delivery pipe 43 whereby the super heated steam is conveyed to its point of use.

A baffle plate 45 is disposed horizontally within the boiler between the entrance to pipe 41 and the pipe connection 25 and vertical baffles as at 46 in Fig. 3 may be located in shell 2 vertically thereof.

To obtain maximum efficiency, the pipe coils 35 are extended practically to the lower end of the super-heater and they are as close together as is practical to place them.

To control the admittance of the heated gases to the super-heater, I have provided a damper within the lower end of shell 18. This damper comprises a downwardly tapered, conical plate 47 fitted and sealed in the lower end of shell 18 and provided with a plurality of openings 48 each of which has a closure member 49 hingedly attached to the plate. A ring 50 is movably mounted upon an annular flange 51 formed on the plate and this ring has links 52 pivotally attached thereto as at 53, and likewise to the closure members 49 so that by rotative movements of the ring, the closures may be moved between open and closed positions. A rod 55 is attached to the ring and extended to a position exteriorly of the shell where it has a handle portion 56 accessible to the operator. When the closure members are in lifted position the openings 48 will be uncovered and heated gases will flow upwardly through the opening 19 and through the damper openings 20 and thus through the super heater, but when they are closed, heat will be cut off from the coils 35 and the steam from the boiler shell 2 will pass through them without additional heating.

Assuming the boiler to be so constructed, its operation, briefly described, is as follows:

The boiler and super-heater are filled with water up to the level indicated. Then, at the start of the operation, the dampers 49 at the lower end of the super-heater are closed. All heat of combustion in the fire box then passes upwardly through the fire tubes 3 of the main boiler. The steam that is thus generated in the upper end of shell 2 passes through the super-heater tubes 35 and is delivered through the pipe 43. After steam has started to flow through the super-heater coils, the dampers at the lower end of shell 18 are opened, thus a part of the heat of combustion from the fire box passes upwardly through the super-heater thereby effecting the super-heating of the steam passing through the coils 35. The extent of the super-heating may be controlled by proper adjustment of dampers between open and closed positions.

By the provision of the pipe connections 21-21 between the opposite sides of the shell 18 and the main fire box extension, and also by the pipe connection 22, the circulation of water is greatly facilitated. Furthermore, the arrangement of the heater provides a considerable amount of additional heating surface. It will be apparent also that since the lining of the super-heating shell is corrugated in horizontal planes, this will greatly strengthen the structure and will further add to the heating surface.

It is also apparent that the provision of the opening 19 in the top of the fire box extension permits of a better distribution of heat. Thus, the boiler is rendered more efficient than otherwise. It is also apparent that with the stack opening into the smoke box located rearwardly from its usual position directly above the burner, the flue sheet 4 will be protected against moisture that may enter the stack. Thus when the boiler is standing in the open and not in use, it is not subjected to disintegration by reason of the collection thereon of water entering the stack.

It is anticipated that many boilers already in existence are subject to conversion to receive super-heaters of the present type merely by formation of the top opening 19 in the fire box extension and the provision of a smoke box 28 to accommodate the super-heater when it is attached over the fire box opening. Such an installation could be easily and quickly made and at

a relatively small expense and will provide not only for super-heating of steam but gives a materially increased heating surface and better circulation.

5 Having thus described my invention, what I claim as new therein and desire to secure by Letters Patent is—

1. A fire tube boiler having an extended fire box provided with a top opening, a super-heater 10 comprising a water jacketed shell forming a heat passage communicating at its lower end with the fire box through said fire box opening, water circulation pipes connecting the water jacketed shell with the boiler, super-heater tubes contained 15 in the passage and means for delivering steam from the boiler through said tubes.

2. A vertical fire tube boiler comprising a smoke box, a fire box formed with an extension having an opening in the top wall of the extension, a 20 super-heater unit comprising a water jacketed shell providing an interior passage communicating at its lower end with the fire box through said opening and at its upper end with the smoke box, a plurality of U-shaped super-heating tubes 25 contained within the passage, a delivery pipe, a manifold having compartments connected respectively with the boiler and with the delivery pipe and providing for flow of steam from the boiler to the delivery pipe through said super-heater tubes, said shell having vertically spaced water 30 circulating connections with the boiler.

3. In a vertical fire tube boiler, a fire box, a super-heater comprising a vertical, tubular shell, having a water jacketing lining spaced therefrom 35 and providing a vertical heat passage communicating at its lower end with the fire box, water circulation connections joining the boiler and water jacketed shell, a steam by-pass connection joining the upper end of the water jacket and boiler and super-heating coils contained in the 40 passage and connected to receive steam therethrough from the boiler.

4. A vertical fire tube boiler comprising a smoke box, a fire box formed with an extension having an opening in the top wall of the extension, a 45 super-heater unit comprising a water jacketed shell providing an interior passage communicating at its lower end with the fire box through said opening and at its upper end with the smoke box,

a plurality of U-shaped super-heating tubes contained within the passage, a delivery pipe, a manifold having compartments connected respectively with the boiler and with the delivery pipe and providing for flow of steam from the boiler to the delivery pipe through said super-heater tubes, said shell having vertically spaced circulating connections with the boiler and a steam by-pass provided between the upper end of the water jacketed shell and boiler.

5. A boiler as stated in claim 4 wherein the super-heater shell is water jacketed by an internally located, horizontally corrugated lining.

6. A vertical fire tube boiler comprising a boiler shell, a smoke box at its upper end provided with a stack connection, a fire box mounting the shell and having a portion extended beyond the shell and provided in the top wall of said extension with an opening, a super-heater unit supported on the said extension comprising a cylindrical shell 20 with an interior lining spaced to provide a water jacket for the shell and forming an interior heat passage opening at its lower end to the fire box through the said wall opening, and at its upper end to the smoke box, a steam by-pass connection 25 between the upper end of the water jacket and boiler, water circulation connections between the water jacket and boiler, super-heater tubes in the heat passage connected to receive steam from the boiler, a damper at the lower end of the passage 30 and means exteriorly of the heater for controlling the position of the damper.

7. A boiler as in claim 6 wherein the stack connection for the fire box is offset from above the main boiler.

8. In a boiler of the character described having a vertical boiler shell, a super-heater exterior of the shell and coextensive therewith and comprising a cylindrical shell forming a heat passage, super-heater tubes contained in the passage 40 through which steam from the boiler is discharged, and said passage being adapted to receive heat directly from the fire box, and a lining for said shell providing a water jacket; said jacket 45 having water circulation connections with the boiler and having a steam connection at its upper end with the boiler.

KNUTE BERGER.
